UNITED STATES PATENT OFFICE.

ALEX SHERPITIS, OF CHICAGO, ILLINOIS.

WIRE ROLLING AND CUTTING DEVICE.

1,367,282.

Specification of Letters Patent.

Patented Feb. 1, 1921.

Application filed October 15, 1919. Serial No. 330,737.

To all whom it may concern:

Be it known that I, ALEX SHERPITIS, a citizen of Russia, residing at Chicago, county of Cook, and State of Illinois, have invented 5 certain new and useful Improvements in Wire Rolling and Cutting Devices, of which the following is a specification.

This invention relates to a wire winding and cutting machine and it has for an object 10 to provide a simple and easily constructed and operated device whereby wire coming from drawing dies or otherwise may be rolled upon a suitable spool or bobbin and separated from the main length.

15 Other objects relate to the provision of means for gripping the main length of wire and holding it in position after being cut, and to the provision of a novel form of cutting means and a novel mounting for the 20 spool permitting its ready withdrawal when full.

For further comprehension of the invention, and of the objects and advantages thereof, reference will be had to the following 25 description and accompanying drawings, and to the appended claims in which the various novel features of the invention are more particularly set forth.

Figure 1 of the drawings is a plan view 30 of a wire winding and cutting machine constructed according to my invention.

Fig. 2 is a rear elevation thereof.

Fig. 3 is an end elevation.

Fig. 4 is a transverse section, this view 35 being taken on the line 4—4 of Fig. 5.

Fig. 5 is a front elevation.

Fig. 6 is a fragmentary transverse sectional elevation showing particularly the knife operating and holding means.

40 Fig. 7 is a side elevation, partly in longitudinal section, of the spool and its novel support.

Fig. 8 is a transverse section on the line 8—8 of Fig. 7.

45 Fig. 9 is a similar view to Fig. 6, but showing the gripper operating and holding means.

The frame of my improved machine as 50 here shown comprises a flat base 1 of oblong shape from which an integral plate-like member 2 extends upward, this member having an angular offset 3 at one end. For convenience I shall hereinafter refer to the member 2, which carries most of the operating 55 parts, simply as the plate.

Journaled upon plate 2 in a vertical row and near the end thereof opposite to the offset 3, is a series of horizontal stub shafts 4, upon which the spools 5 are slidably mounted, while the shafts project a distance approximately double the length of the spools to accommodate the back and forward movement of the spools as the wire winds thereon. The spools 5, each have a sleeve 6 mounted therein and slideable on the shaft 4, the latter being longitudinally grooved as at 7, while the sleeve is slotted and pressed inwardly on one side to form a key 8, engaging in this groove. A flat spring 9, is fixed at one end in the key 8, and its opposite end 60 has a projection 10 which extends partly across the outer face of the spool and prevents displacement of the latter. 65

These stub shafts 4, are rotated in unison by means of a crank handle 11 on a gear 12 70 pivoted on the plate 2, and meshing with an idler pinion 13 which meshes in turn with a second gear 14 on the end of one of the stub shafts, the gear 14 having eccentrically connected thereto as at 15 a connecting rod 16 75 80 which also connects with crank arms 17 on the ends of the other stub shafts 4.

The wires to be wound are indicated at 18 and are led to the machine through apertures 19, in the offset 3 and then between gripping devices which are arranged one above the other and with a common operating means to act in unison upon all the wires. These gripping devices each consist of a disk 20 fixed on the upper end of a pin 21 slideable 85 in a head 22 on the end of a lever arm 23 fulcrumed as at 24 upon studs 25 projecting from the plate 2. A spring 26 surrounds each pin 21 between the disk 20 and head 22 and normally acts to press the disk upward. 90 These disks coöperate with abutment heads 27 fixed on the plate. 95

The opposite ends of levers 23 project through slots 28 in plate 2 and are pivotally connected to a vertical link 29 which is normally pressed upwardly by a spring 30 which bears between the base 1 and the lower end of the link 29. A spring catch 32 having a beveled upper face 33 and a handle 34 is fixed on the base 1 and is adapted to automatically 100 engage the projection 31 on the link when the link is depressed to operate the grippers, a common operating handle for the grippers and cutters being provided, as will be presently pointed out. 105 110

The cutters are arranged on plate 2 a short distance from the grippers just described and comprise fixed knife blades 35 formed on a vertical bar 36 secured to lugs 37 projecting from the plate 2 and having downwardly inclined cutting faces 38. Coöperating with these fixed knives are the movable knives 39 pivoted as at 40 to projection 41 from the plate 2 and having rigidly connected thereto the arms 42 which project through slots 43 in the plate 2 and are pivoted to a link 44, similar to the link 36, at their ends. This link 44 is also normally pressed upwardly by a spring 45 which bears against the lower end thereof, a spring catch 47 similar to the catch 32, being adapted to engage a projection 46 on the link when the link is depressed.

Pivoted to the lug 37 to which the knife bar 36 is fastened at its upper end is a handle 48, this handle passing through an opening 49 in the plate 2. This handle is located between the gripping and cutting devices and is provided with the oppositely projecting angular fingers 50 and 51 which are adapted to engage the upper ends of the respective links 29 and 44 to operate the gripping and cutting devices.

Mounted on studs 52 projecting from the plate 2 adjacent the cutting devices are a series of grooved rollers 53 over which the wires pass. A pair of coöperating friction straps 54 and 55 are mounted upon the plate 2 adjacent the rollers 53 and serve to hold a tension on the wires, these strips being preferably spring-pressed toward each other, in any suitable manner.

The manner of operation of my improved wire winding and cutting machine is as follows:

The wires are led through the openings 19, passing between the fixed and movable members of the grippers, and of the cutters, then over the rollers 53 and between the tension straps 54 and 55 to the spools 5 to which the ends may be secured in any suitable manner.

The spools are then rotated to wind the wires thereon by turning crank handle 11 and rotating gear 12, pinion 13 and gear 14, the connecting rod 16 causing all the shafts 4, and the spools mounted thereon, to rotate. When the spools are wound full the handle 48 is depressed, throwing links 29 and 44 downward and causing the knife blades 39 and gripping disks 20 to move upward, simultaneously severing the wires and gripping the ends thereof. As the links 29 and 44 descend the catches 32 and 47 engage over the projections 31 and 46, holding the knives and gripping disks in operative position. After the spools are removed and new ones placed on the shafts 4 the catches are released and the operation as just described repeated.

Having thus described my invention what

I claim as new and desire to protect by Letters Patent of the United States is as follows:

1. In a wire winding and cutting machine, a series of spool supporting shafts, means for rotating said shafts in unison, a series of cutting devices operatively connected together, a catch adapted to automatically engage and hold said devices when operated, a series of gripping devices operatively connected together, a second catch adapted to automatically engage and hold said gripping devices when operated, and a common operating means for said cutting and gripping devices for elevating said gripping devices to grip the ends of the wire upon the depression of said cutting devices for cutting the wire.

2. In a wire winding and cutting machine, a series of spool supporting shafts, means for rotating said shafts in unison, a series of cutting devices operatively connected together, a catch adapted to automatically engage and hold said devices when operated, a series of gripping devices operatively connected together, a second catch adapted to automatically engage and hold said gripping devices when operated, and a common operating means for said cutting and gripping devices for elevating said gripping devices to grip the ends of the wire upon the depression of said cutting devices for cutting the wire, said means comprising a member adapted to bear freely on said devices.

3. In a wire winding and cutting machine, a series of spool supporting shafts, means for rotating said shafts in unison, a series of cutting devices operatively connected together, and a series of resilient gripping devices operable in unison with said cutting devices, said gripping devices each comprising a pivoted arm, a spring pressed disk carried thereby, and a fixed head with which said disk cooperates in gripping the wires upon the simultaneous depression of the cutting devices for cutting the wires, and elevation of the gripping devices for gripping the ends of the cut wires.

4. In a wire winding and cutting machine, a series of cutting devices each including a pivoted arm, a link connecting said pivoted arms together, a series of gripping devices each including a pivoted arm, and an operating arm adapted to bear on the respective links to operate the said cutting and gripping devices for depressing said cutting devices to cut the wires, and to simultaneously elevate said gripping devices for gripping the ends of the cut wires.

5. In a wire winding and cutting machine, a series of cutting devices each including a pivoted arm, a link connecting said pivoted arms together, a series of gripping devices each including a pivoted arm, and an operating arm adapted to bear on the respective

links to operate the said cutting and gripping devices, said cutting devices to descend and cut the wires and said gripping devices simultaneously to rise and grip the cut wires
5 said operating arm including a pair of oppositely projecting angular fingers which engage the said links.
6. A wire winding and cutting machine comprising a base having a plate extending upwardly therefrom, said base having an angular offset provided with a plurality of perforations through which the wires pass, a series of gripping devices located on said plate adjacent said offset, a series of cutting
10 devices carried by said plate a short distance from said gripping devices, a common means including a pair of vertical links and an arm adapted to bear freely thereon for operating said gripping and cutting devices, said cutting
15 devices to descend and cut the wires and said gripping devices simultaneously to rise and grip the wires, a series of spools also mounted on said plate, means for operating said spools in unison, and tension devices
20 on said plate adjacent said spools.
25

7. A wire winding and cutting machine comprising a base having a plate extending upwardly therefrom, said base having an angular offset provided with a plurality of perforations through which the wires pass, 30 a series of gripping devices located on said plate adjacent said offset, a series of cutting devices carried by said plate a short distance from said gripping devices, a common means including a pair of vertical links and an arm 35 adapted to bear freely thereon for operating said gripping and cutting devices, said cutting devices to descend and cut the wires and said gripping devices simultaneously to ascend and grip the cut wires, a series of spools 40 also mounted on said plate, means for operating said spools in unison, and tension devices on said plate adjacent said spools, said tension devices comprising a pair of vertical straps between which the wires are frictionally engaged. 45

In testimony whereof I have affixed my signature.

ALEX SHERPITIS.
